Patented Aug. 19, 1919.

UNITED STATES PATENT OFFICE.

EDWARD A. McMURTRY, OF CHICAGO, ILLINOIS.

EXPRESSION ORGAN-KEYBOARD.

1,313,711.

Specification of Letters Patent. Patented Aug. 19, 1919.

Application filed September 25, 1916. Serial No. 122,069.

To all whom it may concern:

Be it known that I, EDWARD A. McMURTRY, a citizen of the United States, residing at Chicago, in the county of Cook and State 5 of Illinois, have invented Expression Organ-Keyboards, of which the following is a specification.

The object of my invention is to produce an organ which is highly expressive from 10 the keys, like a piano, and this object is attained by my expression organ keyboard which brings full and complete control of the swell shades under the fingers of the artist as he plays on the keys with varying degrees of force, thereby allowing him to play with both hands and both feet and to control two or more independent swells at the same time,—he may be opening one 15 while closing another in playing on two key- 20 boards.

I deem it advisable to state that in some organs all the swell shades are connected together and move at the same time, the degree of opening governing the power of tone 25 emitted. In other organs the swell shades open one after another, each to its full extent; the number of shades open governing the power of tone emitted. In swells of 30 this type each shade is operated by a separate pneumatic motor which is controlled by an electropneumatic relay, each relay being actuated by closing a fine silver contact at the key-desk. I shall describe my invention as applied to swells of this type operating 35 in a series.

My invention is illustrated in the accompanying drawing in which Figure 1 is a perspective view of my invention in position on an organ. Fig. 2 shows an end 40 view of my invention alone. Fig. 3 is detail view of contact frame with wire contacts in position. Fig. 4 is detail view of valve in damping pneumatic buffer. Fig. 5 represents an ordinary swell box showing 45 two shades of the series type, one being open, and speaking pipes in the swell box. Fig. 6 is a diagram of electrical connections.

Like numbers indicate like parts in all the figures.

50 Elongated inflexible member 1, of wood, aluminum or other suitable material shaped as shown, is pivoted at 2 and 2' and runs the full length of organ keyboard. On its under side, at the free edge, is projection 55 3 covered with felt strip 4 also running the full length of keyboard. Piece 18, of

wood or other suitable material is fastened to member 1 and its projection 28 operates between stops 5 and 6 which restrict motion of free edge of member 1 to about $\frac{1}{4}$ " or 60 less. Also spring 7 keeps member 1 in a down position normally by pressing upward on piece 18 as shown. On member 1 is fastened metal piece 8 with its edge 9 coated with a contact strip of silver, platinum or 65 other suitable material.

Contact wire frame with wires in position is shown in detail in Fig. 3 wherein frame 10 of insulating material, shaped as shown, has pegs of insulating material driven along 70 face 13. On face 14 contact wires 11 are fastened. Each wire has its free end passing into one of the narrow elongated openings formed between the insulating pegs 12. The free ends of these contact wires, which 75 are of silver, platinum or other suitable material, project over edge 15 about $\frac{1}{4}$ " or more and lie flat against face 13 which adjusts them in perfect horizontal alignment.

This contact device is rigidly fastened in 80 such relative position to inclined contact strip 9 that, as strip 9 rises with member 1 it touches and lifts one wire contact 11 after another until all contact wires rest on strip 9 when stop 5 checks further motion 85 of member 1. As each contact wire touches edge 9 electrical connection is made and the electropneumatic relay 30, Fig. 5, in the circuit thus closed allows air to enter its particular pneumatic motor 31 and causes its 90 particular swell shade 32 to fly open. Flexible wire 23 establishes electrical connection with piece 8 and the rest of the circuit. Cable 24 carries an insulated wire for each contact wire 11. There are usually 15 to 95 20 shades on a swell box and there will be, therefore, as many contact wires 11 as there are shades. Walls of the swell are represented at 33, Fig. 5.

Small pneumatic buffer 16 is composed of 100 face 17 and piece 18 which is fastened to member 1. Piece 17, of wood or suitable material is held in a fixed position by bracket 19, and has in it valve at hole 20. This valve is shown in detail in Fig. 4 and 105 is composed of leather piece 21 covering hole 20 on the inside of motor 16. This leather strip has in it a smaller hole 22 than 20. As a result, air enters hole 20 very readily but the moment air attempts to 110 escape leather piece 21 covers hole 20 and air must escape through 22 which is quite

a bit smaller. This buffer acts as a damper for member 1 for it does not allow it to fall back to its original down position too quickly and yet it allows member 1 to rise 5 instantly and easily when keys are struck forcibly against it on strip of felt 4.

During staccato playing this motor or bellows keeps member 1 in a reasonably quiet state and prevents unnecessary or objectionable fluttering of the swell shades. 10

Organ keys are shown at 27, 27', etc. It is desirable that a separate spring 29 (or 29', etc.) be placed under each key as shown. This spring does not touch the key until it 15 (key) is depressed such a distance that key tail touches the felt buffering strip 4 on member 1. When the key has reached this point it just touches spring 29 also, which is very stiff and acts as an auxiliary with spring 7 20 in resisting further downward movement of the key. The auxiliary springs under each key prevent the playing or striking of one hand being felt by the other through member 1 when playing on one keyboard entirely. 25

The operation of my invention is as follows—

As in all organs, keys 27, 27', etc., operate pipe contacts in box 26 through arms 25 30 which rest on the extreme ends of keytails as the one shown. This forms no part of my invention.

Now, when any key (or keys) is depressed the pipe contacts in box 26 are closed and 35 the electropneumatic actions 35, 35', etc., cause the pipes 34, 34', etc., to speak as usual. But as the key (or group of keys) travels downward it touches spring 29 (or 29', etc.) and at the same instant the keytail (or group of keytails) touches felt buffering strip 4 on member 1, and (1) if very 40 light pressure was used in depressing the key (or keys) spring 29 (29', etc.) and spring 7 on member 1 will be strong enough 45 to arrest further motion of the key (or group of keys) and member 1 will not be moved upward at all therefore.

As a result the swell shades will remain in their normal closed position because none of 50 the contact wires 11 have made contact with strip 9. The pipes, therefore, speak in a closed swell box and their tone is extremely soft.

(2) If moderately heavy force was used 55 springs 29 (or 29', etc.) and 7 will not be strong enough to prevent the key (or keys) from moving member 1 and member 1 will move upward against the keytail (or tails) until the pressure of the springs just balances the pressure exerted on the keys. This 60 will not be a full movement of member 1 and as a result a few of the contact wires 11 will rest on contact strip 9, which has moved up with member 1, and the swell shades controlled by these particular contacts will in- 65

stantly fly open. As a result, the pipes speak as before, but this time with some of the swell shades open and their tone is increased a considerable amount.

(3) If, however any key (or group of 70 keys) be struck or depressed with a heavy force, springs 29 (or 29', etc.) and 7 cannot check this force and member 1 is pushed upward by the pressure exerted against it by the keytail (or tails) until stop 5 prevents 75 further movement. Member 1 has traveled its full distance of about $\frac{1}{16}$ " (or less) and contact strip 9 has touched and lifted all the swell contact wires 11 and all the swell shades fly open. As a result the pipes speak 80 as before, but with all the swells open and their tone is very powerful, the full power of the pipes.

It will be seen that the volume of tone (number of swell shades open) is perfectly 85 and completely controlled by the pressure used in playing on the organ keys.

My invention is applicable to any type of swell but for sake of simplicity I selected 90 the series type in the above discussion.

The only requirement is that the contact switch must correspond to the swell in use. This switch is generally a simple modification of that used on the present balanced swell pedal, which is the only means of full 95 swell control at the present time.

Neither is my invention confined to electric organs for it may be applied to others as well.

In an organ of two or more keyboards and 100 two or more swells or swell boxes, any swell or swells may be controlled from any keyboard by a simple coupling well known and understood by those familiar with organ building. In such an organ it is necessary 105 to have one control mechanism, such as described, for each keyboard rendered expressive.

I claim—

1. An organ comprising swell shutters, 110 one or more electro-pneumatic actions for operating the same, switches for placing the actions successively in and out of operation, playing keys, and means controlled by said keys at will for actuating one or more of 115 said switches.

2. In an organ, the combination of swell mechanism including a motor element, playing mechanism, keys for operating said playing mechanism, and an elongated inflexible 120 member controlling said motor element and operable by each of said keys.

3. In an electric organ, the combination of a key, tone-emitters controlled by the same, an electric circuit having a plurality of 125 branches, a plurality of operating devices, one in each branch, means for varying the power of tone emitted by said tone emitters which have been sounded by said key, said means being operable by said operating de- 130

4. An organ comprising playing keys each mounted to be depressed variable distances, an electric circuit having a plurality of branches, a plurality of swell shades each provided with an operating device in one of said branches, a contact member operable by each of said keys and adapted to close the circuit through a variable number of said branches, thereby operating a variable number of said swell shades, the number depending upon the extent of depression of said keys.
5. In an organ, the combination of expression shades, pneumatic motors for operating the same, an electric circuit having a plurality of branches, a plurality of electro-pneumatic relays, one in each branch, controlling the admission of air to said motors, means for successively completing the circuit through any number of said branches, keys actuating said means, and organ tone emitters controlled by said keys.
6. An organ comprising playing keys, a separate resilient means for each key serving to limit the depression of the same, sound producing devices controlled by said keys, swell mechanism, an electric circuit having a plurality of branches, a plurality of contacts, one for each branch, a plurality of electro-pneumatic actions, one in each branch, for operating said swell mechanism, a contact maker operable by said keys and adapted to engage said contacts successively, thereby closing the circuits through a variable number of said branches, the number depending upon the force used in playing on said keys.
7. An organ comprising playing keys, an elongated inflexible member operable by said keys, and a multiple switch actuated by said member.
8. In an organ the combination of playing keys, swell shades, actuating mechanism therefor, means for controlling said actuating mechanism, said means being operable at will by each of said keys.
9. An organ comprising playing keys, an elongated inflexible member operable by said keys, and a plurality of switches successively actuatable by said member.
10. An organ comprising playing keys, swell mechanism including actuating elements, control devices for said actuating elements, said devices being operable by said keys.
11. An organ comprising playing keys, electro-pneumatic swell mechanism, multiple switches for control thereof, and means actuated at will by each of said keys for controlling the operation of said switches.
12. An organ comprising playing keys, electro-pneumatic swells, multiple switches for control thereof, and means for operating one or more of said switches at will by each of said keys.
13. An electric organ comprising playing keys, electro-pneumatic swell shades, multiple contact switch mechanism for controlling said swell shades, and means actuated by each of said keys for controlling said switch mechanism.
14. An organ comprising swell mechanism including operating elements and keys controlling said elements, said keys also controlling the organ tone-emitters.
15. In an organ the combination of a plurality of keys, a plurality of electric switches, and means controlled by each of said keys at will for actuating one or more of said switches.
16. In an organ the combination of a plurality of keys, each mounted to be depressed variable distances, a series of switches operatively connected with said keys, one or more of said switches being operable at will by each of said keys, the number depending upon the amount of depression of said keys.
17. An organ comprising a plurality of keys, each mounted to be depressed variable distances, an elongated inflexible member operable by said keys, electric switches adapted to be actuated successively by said member, the number actuated depending upon the force used in depressing said keys.

EDWARD A. McMURTRY.
